ATTORNEY.

UNITED STATES PATENT OFFICE.

JOHN B. RICKETTS, OF KANSAS CITY, MISSOURI.

VAULT-LIGHT.

1,172,905.

Specification of Letters Patent. Patented Feb. 22, 1916.

Application filed January 16, 1915. Serial No. 2,575.

To all whom it may concern:

Be it known that I, JOHN B. RICKETTS, a citizen of the United States, residing at Kansas City, in the county of Jackson and 5 State of Missouri, have invented certain new and useful Improvements in Vault-Lights, of which the following is a specification.

My invention relates to improvements in vault or sidewalk lights, and one object of 10 the invention is to provide the margins and lap joints of the metal frame with antileak joints, capable of normal contraction and expansion without detriment to the leak-proof qualities of said joints.

15 A further object is to provide a metal frame which may be manufactured at small cost and will not wear smooth from long service.

Other objects of the invention will herein- 20 after appear, and in order that said invention may be fully understood, reference will now be made to the accompanying drawing, in which:

Figure 1 is a broken plan view of the in- 25 vention. Fig. 2 is a broken isometric view showing a lap joint employed in carrying out the invention. Fig. 3 is a broken longitudinal sectional view of the invention. Fig. 4 shows a modified form of joint.

30 In carrying out the invention, I employ a metal frame 1, consisting, preferably, of inexpensive material, such as malleable iron which will not wear smooth from long use.

Said frame has intersecting transverse and 35 longitudinal ribs 2, forming openings for the reception of the usual lenses 3, which rest upon shoulders 2^a, of the ribs 2, where they are held by a suitable elastic cement 4, which allows for the difference in expansion 40 and contraction between the metal frame 1 and the lenses 3.

The borders of the frame 1 are provided with slots 5, so that when said frame is laid upon the usual cement bed 6, and the slots 45 5 are filled with cement, said frame 1 becomes firmly anchored to its bed on the cement becoming set.

That part of the cement in the slots 5, is reinforced by short twisted rods 7, extending 50 down into the bed 6.

In order to prevent moisture or water leaking through the joint between the frame

1 and the cement bed 6, the borders of said frame 1 are provided at their undersides with corrugations or serrations 8, into which 55 the cement becomes embedded and acts as a series of dams in excluding the water or moisture from said joint.

The lap joint between two panels of the frame 1, is provided with serrations 9 and 60 grooves 10, and a strip of sheet lead or other suitable packing 11, is inserted between said joint. The serrations 9 become embedded in the packing 11 and constitute a series of dams that effectually prevent leakage at said 65 joint.

The usual T-bar 12 is placed beneath the lap joint to support the same.

In the modified form disclosed by Fig. 4, the lap joint is dispensed with between the 70 panels of the frame 1^a, and the adjacent margins of said panels are spaced apart to admit a rib 12^a of a supporting bar 12^b, which has a pair of oppositely-disposed flanges 12^c, to support the margins of the 75 panels. The underside of the margins have serrations 9^a, which are embedded in packing strips 11^a, placed upon the flanges 12^c.

Bolts 13 secure the panels upon the flanges 12^c, and the countersunk heads of said bolts 80 are protected from water by lead or other suitable metal 14, whereby the cavities above said heads are closed.

Having thus described my invention, what I claim and desire to secure by Letters 85 Patent, is:

In combination with a pair of spaced ad-joining panels having their bottoms pro- 90 vided with serrations in proximity to their adjacent sides, a bar having a vertical rib 90 extending up into the space between the panels, oppositely disposed flanges on the bar having serrations receiving the panel serrations, soft packing strips between the serrations and abutting the rib, and vertical 95 bolts passed through the flanges, packing strips and panels and located on opposite sides of the rib.

In testimony whereof I affix my signature, in the presence of two witnesses.

JOHN B. RICKETTS.

Witnesses:

F. G. FISCHER,
L. J. FISCHER.
